UNITED STATES PATENT OFFICE

WILLIAM ALFRED STEPHENS, OF LONDON, ENGLAND, ASSIGNOR TO THE BRITISH
SURE SEAL COMPANY LIMITED

APPARATUS FOR THE MANUFACTURE OF RECEPTACLE CLOSURES

Application filed May 28, 1930, Serial No. 456,612, and in Great Britain July 13, 1929.

This invention relates to the manufacture of closure devices for bottles, jars or the like.

It is usual practice to utilize as a closure for a bottle, jar or the like a "Phoenix" closure, i. e. a closure sold under the registered trade-mark "Phoenix", and including a cap (termed in the trade an "inner") which is lodged within a flanged jointed locking ring (termed in the trade a "band"), the flange engaging over the periphery of the cap. Such closures are sold to firms where bottling and presserving are practised and each closure is secured to a filled container by the free edge or the depending edge of the ring being spun or pressed in under a shoulder on the container, the ring then being of channel form. The rings so used have at one end a slot and near the other end a tongue, and these are engaged under pressure to make the jointed ring an endless member. Such a locking ring is usually fractured on removal and accordingly is considered non-replaceable.

In the manufacture of a non-replaceable locking ring, a strip blank is stamped out of strip material, the slot at the one end, hereafter termed "the tail", being cut transversely of the strip and the tongue cut longitudinally at the other end, hereafter referred to as "the head". These operations are effected with machine tools termed a "band die" and in such machine it has been proposed to form the punch so that in cutting the tongue it also lifts it slightly from the band to facilitate the linking operation hereafter described. However, generally speaking, the tongue is merely cut and left in the plane of the strip.

As the present invention has particular reference to the manufacture of Phoenix type of closures, the usual manual operations necessary to produce them will now be described.

The stamped strip is first curled, then the tongue is pried up and lifted slightly from the plane of the strip and the ends linked by a sort of sliding, scraping action, the slot at the tail end being threaded over the tongue.

Very often, as a result of speeding up linking, the strip is bent into a flat elliptical form by the efforts of the operator to quickly place the slot at the free end of the tongue and pull it under the tongue, and whether or not the slot is actually pulled to the root of the tongue will depend on the efficiency of the

effort of the operator. The tongue, which is then overlying the tail of the ring, is hammered down, thereby locking the linked ends of the strip and forming the ring. Each of these operations is usually effected by different operators. It is then required to associate with the jointed ring a cap which is to be used with the ring. Each cap is placed by an operator by hand within a jointed ring (usually distorted as a result of curling), and generally the cap is disposed about $\frac{1}{8}$ " down from one edge of the ring.

In actual practice here again considerable differences in result are obtained, first of all by reason of the difference of the depth of disposal of the cap within the ring; and secondly with regard to the parallelism of the cap to a plane containing an edge of the ring.

The next operation consists in putting the cap with its associated ring in a machine termed a "dial feed press" which centralizes the cap in the ring and turns over the upstanding edge of the ring, thereby forming a flange over the cap of about $\frac{1}{8}$ " deep, that is, corresponding to the depth of the displacement of the cap within the ring. In this form the cap and ring are sent to the place where they will be used on containers, and machines such as described in U. S. Patent No. 1,452,410 may be utilized for fixing such caps with their rings on the containers by turning in the lower edge of the ring under the neck of the container.

In U. S. Patent No. 1,725,602 is described and claimed a method of jointing non-replaceable locking rings whereby the several hand operations referred to are expedited and more accurately effected, and there is described in this specification and in U. S. Patent No. 1,725,601 apparatus whereby the association of bands and inners may be automatically effected as a continuous automatic operation.

In co-pending Application Serial No. 611,673 filed May 16, 1932, I have described a new form of non-replaceable locking ring in which the tongue, instead of being formed in the head, emanates from the head, and the main object of the present invention is to devise a means of mechanically associating the ring and inner and a further object is to simplify the form of machine described in U. S. Patent Nos. 1,725,601 and 1,725,602. A still further object is to improve such mechanism so that scratching and scoring of the

band during joining or assembly is eliminated.

The present invention comprises an apparatus for curling and jointing locking rings comprising in combination a former including resilient means for engaging the band from which the ring is to be made and tongue setting means automatically operable during the curling operation.

- 10 Preferably, the apparatus comprises in combination a rotary former including resilient means projecting from the periphery thereof to engage the band from which the ring is made, a plunger movable through the periphery of the former to set the band tongue and a fixed abutment adapted to actuate the plunger during a curling operation.

The apparatus for curling and jointing non-replaceable locking rings may comprise 20 means adapted to press together the jointed ends of the band during the final rotation of the former, whereby the relative movement between the pressing means and the former is utilized to effect pressing together of the 25 jointed ends by a simple rolling action. To this end a skid block may be employed which moves over the periphery of the former, but in an opposite direction, or a skid block which is stationary may be employed, the 30 block being disposed so as to be operative on the tongue of the band immediately before the ends of the band are jointed together and before the former has completed one revolution.

35 Preferably, however, the jointed ends of the band are pressed together by a freely mounted roller as such a construction entirely eliminates any scratching or scoring on the band by a relatively sliding movement. The 40 roller may be carried on a rocker arm actuated from the former, for instance by a cam provided on the former so as to positively roll back the tongue after a curling and jointing operation.

45 Preferably the former is intermittently actuated from an oscillating member operating over a ratchet, the oscillating member directly operating an ejector for the jointed ring during its return movement whereby the 50 former is cleared for operation during the next forward movement of the oscillating member.

The oscillating member may be provided 55 with an articulated finger and the ejector laterally displaced to the former through the agency of a bell crank said finger wiping over the bell crank during rotation of the former but moving the bell crank to effect ejection while the former is stationary.

60 Preferably, as hereafter more particularly pointed out, the machine is a hand operated machine, the oscillating member being a handle operable to and fro to effect successively curling and jointing and then ejection.

65 The apparatus for curling and jointing

non-replaceable locking rings may comprise in combination a rotating former including resilient means projecting from the periphery thereof to engage the band from which the ring is made, a face on the former for the 70 reception of an inner whereby the inner is located on the former so that the band can be curled and jointed on the inner and resilient means tensioned as a result of locating the inner, whereby the inner is retained 75 on the former during curling and jointing and kicked therefrom when ejected from the former.

Preferably, the resilient means is constituted by a spring disposed across the former 80 and adapted to retain the inner thereon and to kick it therefrom as hereafter more fully referred to.

In order that the invention may be more clearly understood reference will now be 85 made to the accompanying drawings which show by way of example some embodiments of the present invention.

In the drawings:

Figures 1 and 2 are a front elevation and 90 a side elevation respectively of one form of apparatus for curling and jointing bands according to the present invention;

Figure 3 being a plan view of a construction as shown in Figures 1 and 2 modified 95 by the addition of means for automatically supplying inners to the machine.

Figure 4 is a front elevation of the former detached; and

Figure 5 a side elevation thereof.

Figure 6 is an elevation of the apparatus 100 for supplying inners to the machine shown in Figure 3, the parts being in the position when an inner may be pushed on to the former of the apparatus.

Figure 7 is a detailed section on the line VII—VII of Figure 6 showing the inner carrier and means for pushing the inner on to the former.

Figure 8 is a view similar to Figure 6 110 showing the carrier for the inners in position to receive an inner.

Figure 9 shows the form of band locked and applied to an inner by a machine according to the present invention, which band is 115 the subject of my co-pending application Serial No. 611,673.

In the drawings like reference numerals designate the same or similar parts.

Referring now to Figures 1 to 9, and supposing a band as described with reference to Figure 9 is being operated upon:

The machine comprises a rotatable former 11 which carries a spring pressed plunger 12 projecting from the periphery of the former and over which the perforation 10 in a band 1 (see Fig. 9) is passed. This band is the subject of application, Serial No. 611,673, and is more particularly described therein. The former 11 is disposed within 120

spaced guide plates 13 as in the construction described in the prior U. S. Patent, No. 1,725,602. These guide plates include a camming surface 14 which deflects the head of the strip on to the former 11 so that during a rotation of the former 11 the band is curled thereupon.

For the purpose of setting the tongue 5 so that it will readily enter the slot 3 in the tail of the band when the tail becomes superposed over the head as a result of the complete rotation of the former 11, a plunger 15 carried on a rocker 16 pivoted at 17 on the former 11 is employed.

15 The plunger 15 moves in a slot 18 in the former when the rocker 16 is moved about its pivot. This is effected by a trip 19 fixed below the former, as clearly shown in Figure 1.

20 The band on the former is held to the former by the enveloping guide plates 13 aforesaid, the tongue 5 of the band always travelling between the plates so that when the rocker is tripped and the plunger 15 moves away from the centre of the former 11, it strikes the tongue outwardly and between the guide plates, whilst the body of the band is held by the guide plates.

25 During one rotation of the former the band is engaged by the spring pressed plunger 12, carried round, and when the rocker passes the trip the tongue is set back from the former, and as the completion of the rotation approaches, the tip of the 30 tongue enters the slot 3 in the tail of the band, passes through it until the root of the tongue is against the tail and then the jointed ends of the curled band are pressed together as now to be described.

35 40 Pressing means in the form of a freely mounted roller 20 is carried at one extremity of a rocker 21 pivoted at 22 in the guide plates 13, the other end of the rocker being provided with a finger 23 preferably comprised in a slotted plate 24 adjustably connected to the rocker as indicated at 25.

The former 11 comprises a cam 26 conveniently included in a detachable part of a flange 27 of the former, said detachable part being secured in position by screws 28, see Figure 4, the profile of the cam 26 being such as to push the finger 23 at the desired moment and move the rocker 21 about its pivot 22 causing the roller 20 to roll over and press on the jointed head and tail of the band to secure the ends before the former comes to rest.

45 The former 11 is, as clearly indicated in the drawings, intermittently rotated through the agency of an oscillating member 29 provided with a pawl 30 cooperating with a ratchet 31 mounted on a shaft 32 connected by 4:1 gearing to a shaft 33, see Figure 3.

50 The ratchet 31 comprises, Figure 1, four teeth at 90° apart, so that for each step move-

ment of the ratchet one complete revolution of the shaft 33 obtains. On the end of the shaft 33 is screwed the former 11, the former 11 comprising a threaded projection 34 (see Figure 5) which screws into the tapped end 70 of the shaft 33.

Conveniently the oscillating member 29 is extended into a handle 35. By pulling the handle 35 down the pawl 30 moves the ratchet 31 through one step, and as already explained the former 11 is moved through a complete revolution and by reason of control of the setting plunger 15 and the roller 20 by the former 11, the band is curled and jointed, the ends pressed together and the plunger 12 80 depressed out of engagement with the perforation 10 during rotation of the former.

85 It will be seen that the return of the handle 35 does not impart any movement to the former 11 so that with the alternate movements of the handle the former is rotated through one revolution and is then quiescent.

The quiescent state of the former is utilized to effect ejection of the jointed locking ring therefrom, as before the former has 90 come to rest all the necessary operations on the band have been completed. To this end there is mounted on the shaft 33 a collar 36 grooved on the outside as clearly indicated at 37 in Figure 3. In the groove are 95 lodged at opposite ends of a (conveniently horizontal) diameter two shoes 38 carried on arms 39 fixed to shaft 40 running at right angles to the shaft 33 carrying the former 11.

100 On the shaft is provided a short arm 41 conveniently provided with a bowl 42, thereby the arms 39 and the arm 41 are connected together in the manner of bell cranks.

105 By rocking the short arm 41 the shaft 40 is turned and the arms 39 are rocked carrying with them the shoes 38, thereby the collar is laterally displaced towards the former 11. The former 11 is transversely bored at 43a (see Figure 4) for the passage of ejector pins 43 carried by the collar, thereby the lateral 110 displacement of the collar transmitted to the pins causes the pins to engage a curled band and push it off the former 11.

To actuate this ejector whilst the former 11 is quiescent the oscillating member 29 is 115 provided with an articulated finger 44 fixed to a stub 29a formed on the member 29. During the downward movement of the handle 35 the finger 44 wipes the bowl 42 on the short arm 41, but on the return of the handle, that 120 is, while the former 11 is quiescent, the finger presses down the lever 41 causing the lateral displacement of the collar 36 and the ejection of the band as hereinbefore described.

125 The former 11, guide plates 13 and oscillating member may conveniently be mounted on a base plate 45 to provide a unit structure which may include short standards 46 carrying bearings 47 and 48 for the shafts 32 and 33 respectively, and an adjustable 130

stop 49 may be included on the base plate to limit the downward movement of the handle 35 so that only a quarter of the revolution is imparted to the shaft 32.

5 To assure correct position of the former 11 after a curling operation, whereby a registration of the borings 43a in the former with the ejector pins 43 is procured, the former 11 may be provided also with a shoulder 50, which is engaged by a hooked end 51 (see Figure 1) of a catch lever pivoted at 52 between the guide plates 13, the said lever including a tail 53.

15 The arrangement of parts is such that when the handle 35 is pulled down in a clockwise direction through an angle of 90° the articulated finger 44 after wiping the bowl 42 is brought up against the catch lever, causing the hooked end 51 thereof to be disposed in the path of the shoulder 50 on the former 11, thereby arresting it at the moment when there is registration between the ejector pins 43 and the borings 43a in the former 11.

25 It will be noted that the tail 53 of the catch lever extends under the bowl 42. By such an arrangement, when the handle 35 is returned to eject the curled band by the agency of the articulated finger 44 bearing on the bowl 42 the latter bears in turn on the tail 53, thereby removing the hooked end 51 of the catch lever from the shoulder 50 of the former 11, leaving the latter free for the next curling operation.

35 As in prior U. S. Patent No. 1,725,602 the former includes a face 54 over which an inner may be disposed with its edge on the former so that a band may be curled and jointed on the former, thereby an associated inner and locking ring will be ejected during the return of the handle 35.

45 Although manual means are described for operating the machine, obviously any automatic means may be provided to produce continuously the alternate intermittent movements of the former and ejector.

55 On the guide plates 13 a feed guide 55 may be mounted in juxtaposed relation to the former, thereby bands may be fed to the former in correct register with the plunger, or if the machine is automatically operated automatic means may be provided for feeding forward strips to the plunger in continuous succession, and in combination therewith means may be provided for automatically supplying in succession inners to the former, for instance as described in U. S. Patent No. 1,725,602.

65 A great advantage of apparatus as hereinbefore described is the completely positive action obtained and the absence of springs (except for one on the plunger).

75 Alternatively, as illustrated in Figures 3, 6 and 7, means for feeding an inner actuated from the handle 35 may be provided. To

this end there may be mounted on the front of the base plate 45, as viewed in Figure 6, an open framework 56 including an upper horizontal part 56a carrying a parallel rail 57, on which slides a carrier 58 held thereto by the said upper part 56a of the open framework 56, and being grooved, as clearly indicated at 58e (see Figure 7) to ride on the rail 57.

The open frame supports a bracket 59 for 75 a chute 60 inclined to the vertical, as clearly shown in Figure 3, and arranged to deliver inners to the carriage when in the position shown in Figure 6.

80 As most clearly shown in Figures 7 and 8, the carrier 58 comprises a shaped portion 58a to hold an inner received from the chute 60, and retaining the position slightly inclined from the vertical. If then the carriers move to the right, that is, from the position shown in Figure 8 to the position shown in Figure 6, a part 58b, see particularly Figure 8, of the carrier passes under the chute 60, holding up the inners therein from falling, whilst the inner just previously dropped into the shaped portion 58a of the carrier is disposed in front of the former 11.

85 The carrier 58 also comprises a groove 58c formed symmetrically about the horizontal diameter of an inner when within the shaped portion 58a of the carrier, the groove 58c terminating in a slot 58d.

90 Carried on a support 61 conveniently comprised in the feed guide 55 for the bands to be curled on the former 11 is a blade spring 100 62, and when the carrier is in the position shown in Figure 8 the tip of the spring 62 is disposed in the groove 58c.

95 As the carriage moves to the right the groove passes under the spring 62 until the 105 slot 58d is brought thereunder, when the spring 62 pushes through the slot 58d, as clearly shown in Figure 3, and engages the back of an inner within the shaped portion 58a of the carriage 58, first tilting the inner into the vertical position and then moving it laterally on to the former 11 being lodged within the circular portion of the outer guide plate 13.

110 To achieve correct movements of the carrier with regard to the other portions of the machine there is mounted on the stub 29a (see particularly Figs. 1 and 6) an arm 63 which, with the handle 35, forms in nature a bell crank. To the free arm 63 is pivoted at 64 an abutment 65, slotted at its free end as indicated at 66, see Figures 6 and 8, for relative movement over a pin 67 carried by a lever 68 pivoted at 69 on a support 57a for the rail 57 carried by the open frame 56. The lever 68 is hinged at 70 to the carriage 58, preferably integrally, by means of a slot bar 71 held to the carriage by pins 72, a spring 73 also connecting the lever 68 to the carriage 58.

The length of the slot 66, of the abutment 65 and of the lever 68 is arranged so that movement of the handle 35 to produce ejection of an inner is lost motion as regards movement of the carriage, and not until the part of the movement of the handle for ejection has in fact been completed is the lever 68 actuated to move the carriage.

In Figure 8 the angle between the position of the arm 63 and the line A represents the angle of movement of the arm 63, which is idle, and the angle between the lines A—B on Figure 8 represents the movement which is effective as regards movement of the carriage.

By providing the spring 73 and the slotted bar 71 as a means of connecting the lever 68 to the carriage 58 jarring is entirely eliminated, because when the end of the slot 66 comes against the pin 67 there is an extension of the spring 73 accompanied by the movement of the bar 71 over the pins 72, and when this movement is finished the carriage then moves.

Preferably, to assist retention of an inner on the face 54 of the former and to assist ejection of an associated inner and band, there is stretched across the face of the former a spring or equivalent resilient member, which is tensioned as a result of disposing the inner on the former, thereby the cap is retained on the former and on being ejected is again kicked therefrom by the spring or its equivalent.

In the preferred form and as shown in the accompanying drawings, the spring 74 is carried across the orifice of the guide plates 13 and conveniently is secured at one end to the pivot 22 of the rocker 21 and anchored at the other end to a pin 75 on the feed guide 55.

The disposition of the spring is clearly shown in Figures 4 and 5, the spring being indicated in Figure 1 by a line coincident with its axis to retain clearness in the drawings.

As the inner is placed over the face 54 of the former, the spring 74 is deflected upwardly between its anchors and engages over the back of the inner as clearly shown in Figure 5, thereby the inner is retained on the former. On ejection the lateral displacement of the inner again distends the spring which as soon as it is free of the former is shot downwardly by the spring and clear ejection of the inner and band obtained.

What I claim is:—

1. In apparatus for curling and jointing a band having a tongue at one end and a slot at the other so as to form a locking ring, the combination comprising a rotatable former, a plunger movably mounted in said former and adapted to project from the periphery of said former, said plunger being adapted to set said tongue, means for curling said band around said former and a fixed abutment,

said abutment being adapted to actuate said plunger at a predetermined period of the rotation of said former.

2. In apparatus for curling and jointing a band having a tongue at one end and a slot at the other so as to form a locking ring, the combination comprising a former, resilient means in said former for engaging said band and setting said tongue, means for curling said band around said former, means for engaging the slotted end of said band with said tongue, said tongue setting means being operable automatically during the curling operation, means for rotating said former, and means for pressing together the jointed ends of the band during the last portion of the rotation of the former.

3. In apparatus for curling and jointing a band having a tongue at one end and a slot at the other so as to form a locking ring, the combination comprising a former, resilient means in said former for engaging said band and setting said tongue, means for curling said band around said former, means for engaging the slotted end of said band with said tongue, said tongue setting means being operable automatically during the curling operation, means for rotating said former, and means for pressing together the jointed ends of the band during the last portion of the rotation of the former, said pressing means and former being capable of relative movement, said movement being utilized to press together the jointed ends by a simple rolling action.

4. In apparatus for curling and jointing a band having a tongue at one end and a slot at the other so as to form a locking ring, the combination comprising a former, resilient means in said former for engaging said band and setting said tongue, means for curling said band around said former, means for engaging the slotted end of said band with said tongue, said tongue setting means being operable automatically during the curling operation, means for rotating said former, a rocker arm, a roller mounted in said rocker arm, said roller being adapted to press together the jointed ends of the band, and a cam on said former, said cam being adapted to positively operate the roller after a curling and jointing operation.

5. In apparatus for curling and jointing a band having a tongue at one end and a slot at the other so as to form a locking ring, the combination comprising a former, resilient means in said former for engaging said band and setting said tongue, means for curling said band around said former, means for engaging the slotted end of said band with said tongue, said tongue setting means being operable automatically during the curling operation, means for rotating said former, said former being rotated intermittently, said means for rotating said roller including an

oscillating member and a ratchet, means for pressing together the jointed ends of said band during the final rotation of said former, and an ejector carried by said former, said ejector being actuated directly by said oscillating member during its return movement whereby the said former is cleared for operation during the next forward movement of said oscillating member.

10 6. In apparatus for curling and jointing a band having a tongue at one end and a slot at the other so as to form a locking ring, the combination comprising a former, resilient means in said former for engaging said band

15 and setting said tongue, means for curling said band around said former, means for engaging the slotted end of said band with said tongue, said tongue setting means being operable automatically during the curling operation

20 7. In apparatus for curling and jointing a band having a tongue at one end and a slot at the other so as to form a locking ring, the combination comprising a former, resilient means in said former for engaging said band

25 and setting said tongue, means for curling said band around said former, means for engaging the slotted end of said band with said tongue, said tongue setting means being operable automatically during the curling operation

30 8. In apparatus for curling and jointing a band having a tongue at one end and a slot at the other so as to form a locking ring, the combination comprising a former, resilient means in said former for engaging said band

35 and setting said tongue, means for curling said band around said former, means for engaging the slotted end of said band with said tongue, said tongue setting means being operable automatically during the curling operation

40 9. In apparatus for curling and jointing a band having a tongue at one end and a slot at the other so as to form a locking ring, the combination comprising a former, resilient means in said former for engaging said band

45 and setting said tongue, means for curling said band around said former, means for engaging the slotted end of said band with said tongue, said tongue setting means being operable automatically during the curling operation

50 10. In apparatus for curling and jointing a band having a tongue at one end and a slot at the other so as to form a locking ring, the combination comprising a former, resilient means in said former for engaging said band

55 and setting said tongue, means for curling said band around said former, means for engaging the slotted end of said band with said tongue, said tongue setting means being operable automatically during the curling operation

60 11. In apparatus for curling and jointing a band having a tongue at one end and a slot at the other so as to form a locking ring, the combination comprising a former, resilient means in said former for engaging said band

65 and setting said tongue, means for curling said band around said former, means for engaging the slotted end of said band with said tongue, said tongue setting means being operable automatically during the curling operation

former and projecting from the periphery thereof, said plunger being adapted to engage said band and set said tongue, and said guide plates having a camming surface, said surface deflecting the head of said band on to the former so as to curl the band on the said former during the rotation thereof, a rocker pivoted on said former to actuate said plunger, said former having a slot therein in which said plunger moves, and a trip fixed below said former and co-operating with said rocker.

70 12. In apparatus for curling and jointing a band having a tongue at one end and a slot at the other so as to form a locking ring, the combination comprising a former, resilient means in said former for engaging said band

75 and setting said tongue, means for curling said band around said former, means for engaging the slotted end of said band with said tongue, said tongue setting means being operable automatically during the curling operation

80 13. In apparatus for curling and jointing a band having a tongue at one end and a slot at the other so as to form a locking ring, the combination comprising a former, resilient means in said former for engaging said band

85 and setting said tongue, means for curling said band around said former, means for engaging the slotted end of said band with said tongue, said tongue setting means being operable automatically during the curling operation

90 14. In apparatus for curling and jointing a band having a tongue at one end and a slot at the other so as to form a locking ring, the combination comprising a former, resilient means in said former for engaging said band

95 and setting said tongue, means for curling said band around said former, means for engaging the slotted end of said band with said tongue, said tongue setting means being operable automatically during the curling operation

100 15. In apparatus for curling and jointing a band having a tongue at one end and a slot at the other so as to form a locking ring, the combination comprising a former, resilient means in said former for engaging said band

105 and setting said tongue, means for curling said band around said former, means for engaging the slotted end of said band with said tongue, said tongue setting means being operable automatically during the curling operation

110 16. In apparatus for curling and jointing a band having a tongue at one end and a slot at the other so as to form a locking ring, the combination comprising a former, resilient means in said former for engaging said band

115 and setting said tongue, means for curling said band around said former, means for engaging the slotted end of said band with said tongue, said tongue setting means being operable automatically during the curling operation

120 17. In apparatus for curling and jointing a band having a tongue at one end and a slot at the other so as to form a locking ring, the combination comprising a former, resilient means in said former for engaging said band

125 and setting said tongue, means for curling said band around said former, means for engaging the slotted end of said band with said tongue, said tongue setting means being operable automatically during the curling operation

plates having a camming surface, said surface deflecting the head of said band on to the former so as to curl the band on the said former during the rotation thereof, said

5 means for rotating the former intermittently including a shaft on which said former is mounted, a second shaft, gearing having 1:4 ratio between said shafts, a ratchet wheel having four teeth spaced 90° apart on said 10 second shaft, an oscillating member, and a pawl carried by said oscillating member and co-operating with said ratchet.

12. In apparatus for curling and jointing a band having a tongue at one end and a slot in the other so as to form a locking ring, the combination with a former, of means for rotating said former intermittently, spaced guide plates between which said former is mounted, a spring pressed plunger in said 20 former and projecting from the periphery thereof, said plunger being adapted to engage said band and set said tongue, and said guide plates having a camming surface, said surface deflecting the head of said band on 25 to the former so as to curl the band on the said former during the rotation thereof, and means for ejecting the jointed locking ring, said ejecting means including a shaft on which said former is mounted, a collar having a groove on the outside on said shaft, a second shaft extending at right angles to said first shaft, arms fixed to said shaft, shoes carried on said arms and engaging said groove, a second arm carried by said second, 30 shaft, a bowl on said arm, all of said arms being connected together by bell cranks, an oscillating member, an articulated finger on said oscillating member, said finger co-operating with said arm, said former being transversely bored, and ejector pins carried by 35 said collar and passing through said transverse borings.

13. In apparatus for curling and jointing a band having a tongue at one end and a slot in the other so as to form a locking ring the combination with a former, of means for rotating said former intermittently, spaced guide plates between which said former is mounted, a spring pressed plunger in said 40 former and projecting from the periphery thereof, said plunger being adapted to engage said band and set said tongue, and said guide plates having a camming surface, said surface deflecting the head of said band on 45 to the former so as to curl the band on the said former during the rotation thereof, and means for ejecting the jointed locking ring, said means including a shaft on which said former is mounted, said former being transversely bored, a collar mounted on said shaft, 50 ejector pins on said collar, said pins engaging said borings, means for actuating said collar, and means for obtaining registration between said borings and said pins, said last mentioned means including a shoulder on

said former and a catch lever having a tail pivoted between said guide plates, said catch lever having a hooked end for engagement with said shoulder, said catch co-operating with the collar actuating means so as to bring 70 the hooked end of the catch into and out of engagement with said shoulder.

14. In apparatus for curling and jointing a band having a tongue at one end and a slot in the other so as to form a locking ring the combination with a former, of means for rotating said former intermittently, spaced guide plates between which said former is mounted, a spring pressed plunger in said former and projecting from the periphery thereof, said 75 plunger being adapted to engage said band, and set said tongue, and said guide plates having a camming surface, said surface deflecting the head of said band on to the former so as to curl the band on the said former during 80 the rotation thereof, and means for feeding an inner to said former, said means including an open framework having a parallel rail, a carriage sliding on said rail, and a chute inclined to the vertical on said framework and 85 adapted to deliver inners to said carriage.

15. In apparatus for curling and jointing a band having a tongue at one end and a slot in the other so as to form a locking ring the combination with a former, of means for rotating said former intermittently, spaced guide plates between which said former is mounted, a spring pressed plunger in said 90 former and projecting from the periphery thereof, said plunger being adapted to engage said band and set said tongue, and said guide plates having a camming surface, said 95 surface deflecting the head of said band on to the former so as to curl the band on the said former during the rotation thereof, and 100 means for feeding an inner to said former, said means including an open framework having a parallel rail, a carriage sliding on said rail, and a chute inclined to the vertical on said framework and 105 adapted to deliver inners to said carriage, and means for moving said carriage into a position for receiving inners from said chute and for delivering said inners to the former.

16. In apparatus for curling and jointing a band having a tongue at one end and a slot in the other so as to form a locking ring the combination with a former, of means for rotating said former intermittently, spaced 110 guide plates between which said former is mounted, a spring pressed plunger in said former and projecting from the periphery thereof, said plunger being adapted to engage said band and set said tongue, and said 115 guide plates having a camming surface, said surface deflecting the head of said band on to the former so as to curl the band on the said former during the rotation thereof, and means for feeding an inner to said former, said means including an open framework 120

having a parallel rail, a carriage sliding on said rail, and a chute inclined to the vertical on said framework and adapted to deliver inners to said carriage, said carriage having a groove therein formed symmetrically about the horizontal diameter of the inner and a slot in which said groove terminates, a fixed support, and a blade spring carried by said support and co-operating with said groove and slot, said blade spring being adapted to engage said inner, first tilting said inner into a vertical position and then moving said inner laterally on to the former.

17. In apparatus for curling and jointing a band having a tongue at one end and a slot in the other so as to form a locking ring the combination with a former, of means for rotating said former intermittently, spaced guide plates between which said former is mounted, a spring pressed plunger in said former and projecting from the periphery thereof, said plunger being adapted to engage said band and set said tongue, and said guide plates having a camming surface, said surface deflecting the head of said band on to the former so as to curl the band on the said former during the rotation thereof, and means for feeding an inner to said former, said means including an open framework having a parallel rail, a carriage sliding on said rail, and a chute inclined to the vertical on said framework and adapted to deliver inners to said carriage, a carriage for supplying inners to said former, and means actuating said carriage in synchronism with the other operative elements of said apparatus.

18. In apparatus for curling and jointing a band having a tongue at one end and a slot in the other so as to form a locking ring the combination with a former, of means for rotating said former intermittently, spaced guide plates between which said former is mounted, a spring pressed plunger in said former and projecting from the periphery thereof, said plunger being adapted to engage said band and set said tongue, and said guide plates having a camming surface, said surface deflecting the head of said band on to the former so as to curl the band on to the former during the rotation thereof, and means for feeding an inner to said former, said means including an open framework having a parallel rail, a carriage sliding on said rail, and a chute inclined to the vertical on said framework and adapted to deliver inners to said carriage, a pivotally mounted arm, means for actuating said arm, a slotted abutment pivoted to one end of said arm, a feed carriage for inners, a framework in which said carriage is slidably mounted, a lever pivotally mounted on said framework, a pin on said lever engaging said slotted abutment, a slotted bar pivotally connected to said lever, means such as pins connecting said

bar to said carriage, and a spring connecting said lever to said carriage.

19. Apparatus according to claim 18 wherein the length of the slot of the abutment and the length of the lever are such that a portion of the movement of the actuating means for the arm is lost motion as regards motion of said carriage.

20. In apparatus for curling and jointing a band having a tongue at one end and a slot in the other so as to form a locking ring the combination with a former, of means for rotating said former intermittently, spaced guide plates between which said former is mounted, a spring pressed plunger in said former and projecting from the periphery thereof, said plunger being adapted to engage said band and set said tongue, and said guide plates having a camming surface, said surface deflecting the head of said band on to the former so as to curl the band on the said former during the rotation thereof, a spring extending across the space between said guide plates, a feed guide for bands adjacent one of said guide plates, one end of said spring being attached to said feed guide, a mounted rocker pivotally mounted on the other guide plate, the other end of said spring being attached to the pivot point of said rocker, and means for feeding an inner to said former, the arrangement being such that when an inner is placed over the face of the former the said spring is deflected upwardly and engages over the back of the inner so as to retain it on the former.

21. In apparatus for curling and jointing a band slotted at one end and having a terminal tongue at the other end so as to form a locking ring the combination with a former, of means for rotating said former intermittently, spaced guide plates between which said former is mounted, a spring pressed plunger in said former and projecting from the periphery thereof, said plunger being adapted to engage said band, and said guide plates having a camming surface, said surface deflecting the head of said band on to the former so as to curl the band on the said former during the rotation thereof and to thread the slotted end over the tongue.

22. In apparatus for curling and jointing a locking ring the combination comprising a rotatable former, a resilient plunger in said former for engaging a band having a terminal tongue at one end and a slot at the other and from which the said locking ring is to be made and for setting the tongue, guides for the slotted end of said band being disposed to constrain said slotted end onto the former and thread the slot over the set tongue, and means for pressing together the jointed ends, said last-mentioned means being operable automatically during the curling operation.

WILLIAM A. STEPHENS.
